SOLUBILIZING OF MINERAL, VEGETABLE, AND ANIMAL OILS FOR COSMETIC, PHARMACEUTICAL, AND INDUSTRIAL PURPOSES

Irwin I. Lubowe, Scarsdale, N.Y.
(667 Madison Ave., New York 21, N.Y.)

No Drawing. Filed Dec. 10, 1956, Ser. No. 627,112

6 Claims. (Cl. 252—364)

The present invention relates to solubilizing of mineral, vegetable and animal oils in low molecular weight water miscible or water soluble alcohols, such as methyl, ethyl and isopropyl alcohol.

It has not been readily possible to prepare clear non-separating solutions of high molecular weight vegetable or mineral oils with low molecular weight aliphatic alcohols.

Normally mixtures of low molecular weight alcohols and high molecular weight oils of mineral, vegetable or animal origin will readily separate, and if prepared as emulsions will have diminished pharmaceutical and therapeutic effectiveness, cosmetic consumer acceptance, industrial applicability and efficiency.

It is the primary object of the present invention to provide a novel solubilized mineral, vegetable and animal oil composition in which such oils will be dispersed in low molecular weight alcohols and which product may be used as a base for cosmetic preparations such as hair tonics, hand lotions, sun screening preparations, and aftershave lotions, as well as, facial astringents, anti-perspirant preparations, and anti-dandruff preparations.

Still further objects and advantages will appear in the more detailed description set forth below, it being understood, however, that this more detailed description is given by way of illustration and explanation only and not by way of limitation, since various changes therein may be made by those skilled in the art without departing from the scope and spirit of the present invention.

In accomplishing the above objects, it has been found satisfactory to solubilize mixtures of low alcohols (1 to 3 carbon atoms) and oils (24 to 100 carbon atoms) in major proportion (50 to 100%) by addition of minor proportions of fatty alcohols having 10 to 24 carbon atoms.

The solubilizing combination is used as a solubilizing agent in a proportion less than the low alcohol (1 to 3 carbon atoms) and oil (24 to 100 carbon atoms).

The most satisfactory mixer or additive combinations are those which include saturated fatty alcohols having from 10 to 24 carbon atoms, and desirably from 12 to 18 carbon atoms.

These high molecular weight fatty alcohols may be used singly or in combination, and should preferably constitute 50 to 100% of the additive combination and between 5% to 20% of the final combination containing the mineral, animal or vegetable oil and the low molecular weight water soluble fatty alcohol. These combinations are utilized in non-aqueous compositions.

In mixing to form water clear non-cloudy permanent liquid mixture for storage and shipment, the amount of water present should always be kept less than 10% and if possible less than 1% or 1% since most effective

2

permanent mixtures are obtained without separation in the absence of water.

Although unsaturated fatty alcohols are preferred, it is also possible to utilize saturated fatty alcohols or even hydroxylated fatty alcohols as for example in amounts from 10% to 25% of the saturated fatty alcohol by itself or in the mixer combination.

The preferred amount of fatty alcohols is 20% of the total mixture.

10 Among the fatty alcohols which may be used are the following:

Lauryl alcohol
Myristyl alcohol
Oleyl alcohol
Stearyl alcohol
Palmityl alcohol
Cetyl alcohol
Linoleyl alcohol
Linolenyl alcohol
Ricinoleyl alcohol
Arachadecyl alcohol

Another satisfactory combination is a mixture of lauryl alcohol and myristyl alcohol in proportions of 25 three of the former to one of the latter.

In the preferred embodiment, it is desirable to provide a mixture of a major proportion of an animal, mineral or vegetable oil and a low molecular weight aliphatic alcohol in the presence of 5 to 20% of one of the following miscibility inducing combinations:

Mixture A

	Percent
Lauryl alcohol	62
Myristyl alcohol	25
Cetyl alcohol	13

Mixture B

Lauryl alcohol	70
Oleyl alcohol	30

Mixture C

Oleyl alcohol	60
Myristyl alcohol	40

Mixture D

Oleyl alcohol	50
Linoleyl alcohol	50

Mixture E

Lauryl alcohol	70
Ricinoleyl alcohol	30

In general the above solubilizing combinations may include low molecular weight aliphatic alcohols having 1 to 3 carbon atoms, such as ethyl, propyl, isopropyl and methyl.

It is usually desirable to use combinations of 2 to 3 of the fatty alcohols having 14 to 24 carbons, in an amount ranging from 5 to 15% of the oil and low alcohol mixture.

60 Cetyl, palmityl, myristyl, lauryl, oleyl, linoleyl, linolenyl, stearyl, decyl, ricinoleyl, behenyl, arachindyl and erucyl fatty alcohols may be substituted in or added to Examples A to E.

Preferably the solubilized combination contains from 20 to 50% of the animal, vegetable or mineral oils, and 20 to 50% of the low alcohol and from 5 to 20% of the fatty alcohol (12 to 24 carbon atoms).

The resultant compound contains from 20 to 50% of a low molecular weight water soluble aliphatic alcohol, such as ethyl or isopropyl alcohol. Methyl alcohol may be used in industrial products, instead of ethyl or isopropyl alcohol.

Among the other fatty alcohol combinations which may be used are the following:

Examples	F	G	H	I
Decyl	5	5	1½	
Lauryl	5	70	60	
Myristyl	20	25	25	30
Cetyl	40	2	15	30
Stearyl	20	2	1	40
(all parts by weight)				

Instead of myristyl, oleyl or lauryl alcohols, it is possible to use other saturated or unsaturated or hydroxylated fatty alcohols having from 12 to 24 carbon atoms.

In the preferred composition there is employed about 5 to 20% of the above solubilizing combinations.

The preferred mineral oil which is used in about 20 to 40% proportion is light or heavy petrolatum.

The preferred vegetable oil is sesame oil, soya bean oil, cottonseed oil or corn oil, which is used in the amount of 20 to 60%.

Sweet almond oil, apricot kernel oil, sunflower seed oil, peach kernel oil, safflower oil, tung oil, avocado oil, linseed oil, pine oil, olive oil, wheat germ oil, tallow oil, rice bran oil, corn oil, rosin oil, and peanut oil may also be employed.

Animal oils which may be used are lanolin, Neat's foot oil, whale oil, bone oil, sperm oil, codliver oil and the like.

To give specific examples:

EXAMPLE I

	Parts by weight
Light petrolatum oil	20 to 60
Alcohol ethyl or isopropyl	40
Solubilizing combination	10

EXAMPLE II

	Parts by weight
Cottonseed oil	20 to 40
Alcohol ethyl or isopropyl	40
Solubilizing combination	15

EXAMPLE III

	Parts by weight
Sesame oil	40
Alcohol ethyl or isopropyl	40
Solubilizing combination	10

EXAMPLE IV

	Parts by weight
Neat's foot oil	20 to 50
Ethyl alcohol	20 to 50
Solubilizing combination	10 to 20

The products produced are stable, clear, translucent solubilized oil.

The solubilizing combinations are selected from Examples A to E.

The above compositions may be used in cosmetics, pharmaceuticals, polishes, abrasive and buffering suspensions, paints and waxes, dry cleaning compounds, hydraulic fluids, degreasing compounds, insecticides, weed killers and special lubricants.

To give some additional examples:

EXAMPLE V

	Parts by weight
Ethyl alcohol	50
Petrolatum	20
Oleyl alcohol	10

EXAMPLE VI

	Parts by weight
Isopropyl alcohol	20
Light petrolatum	20
Virgin olive oil	20
Lauryl alcohol	10

EXAMPLE VII

Oleyl alcohol	15
Mineral oil	15
Peanut oil	50
Isopropyl alcohol	40

The above compositions are particularly useful in cosmetics in that they will be highly stable over a wide range of temperatures for long periods of time without separation.

10 All the compositions are miscible with methyl, ethyl or isopropyl alcohol in any proportions.

The freezing point of the composition is depressed and better lubricating properties are obtained in machinery bearings, as well as in cutting oil used in metal working industries.

15 It is possible to include amounts of essential oil in the range from 2 to 20% in the above compositions.

EXAMPLE VIII

20 To give an example of a sun-screening compound:

	Parts by weight
Digalloyl oleate	5
Isopropyl alcohol	15
25 Myristyl alcohol	15
Light petrolatum	40
Ethyl alcohol	30

EXAMPLE IX

Silicone hand lotion

	Parts by weight
Low viscosity silicone oil, 1,000 cs.	15
Neat's foot oil	15
Isopropyl alcohol	40
35 Lauryl alcohol	10

EXAMPLE X

Hair spray

	Parts by weight
40 Isopropyl ester of lanolin	10
Isopropyl alcohol	20
Silicone oil viscosity 1,000 cs.	10
Polyvinyl pyrrolidine	10
Oleyl alcohol	5
Freon	25
45 Dichloro tetra fluoro ethane	

EXAMPLE XI

Insecticide solution

	Parts by weight
50 Mineral oil (light)	30
Isopropyl alcohol	30
Lauryl alcohol	10
2-4 hexandiol	5
55 Insecticide (dimethyl phthalate)	5

EXAMPLE XII

Anti-seborrheic hair lotion

	Parts by weight
60 Estrogenic hormone	1/10
Isopropyl ester of lanolin	30
Palmitic alcohol	10
Ethyl alcohol	50
65 Acetyl methionine	5
Genite (2-4 diphenyl ester benzene sulfonic acid)	5

EXAMPLE XIII

Anti-perspirant

70 Aluminum sulfate	25
Sesame oil	20
Oleyl alcohol	10
Hexachlorophene	2
75 Ethyl alcohol	45

EXAMPLE XIV

After-shave lotion

Peanut oil	15
Oleyl alcohol	5
Ethyl alcohol	55

EXAMPLE XV

Hair Lacquer

Silicone oil (alcohol soluble)	5
Isopropyl lanolin	15
Protein hydrolysates	5
Polyvinyl pyrrolidone	5
Oleyl alcohol	10
Freon	30

EXAMPLE XVI

Permanent waving solution

Thioglycollic acid	15
Ammonium thioglycolate	15
Olive oil	10
Lauryl alcohol	10

EXAMPLE XVII

Solid cologne

Sodium stearate	10
Zinc sulfocarboxylate	10
Sesame oil	25
Lauryl alcohol	15
Myristyl alcohol	5
Ethyl alcohol	45

EXAMPLE XVIII

Transparent soap

Sodium stearate	50
Peanut oil	10
Glycerol	10
Cetyl alcohol	10
Lauryl alcohol	10
Ethyl alcohol	30

EXAMPLE XIX

Scalp stimulating lotion

Resorcinol mono-acetate	5
Tincture of capsicum	5
Zinc phenol sulfonate	5
Cottonseed oil	20
Lauryl alcohol	10
Ethyl alcohol	45

EXAMPLE XX

Acne preparation

Estrone	2
Resorcinol monoacetate	5
Salicylic acid	3
Peanut oil	17
Isopropyl alcohol	50
Lauryl alcohol	15
Myristyl alcohol	5

EXAMPLE XXI

Solubilized olive oil composition

Olive oil	20
Isopropyl alcohol	60
Lauryl alcohol	10
Myristyl alcohol	3

EXAMPLE XXII

Solubilized peanut oil composition

Peanut oil	20
Isopropyl alcohol	60
Lauryl alcohol	10
Methyl alcohol	3

Where lauryl and myristyl compounds are used together as high molecular weight fatty alcohols, the proportion of lauryl should be 2 to 4 times the proportion of myristyl alcohol.

It is apparent that many variations may be made in the formulae.

In the examples above set forth, the specific ingredients described may be widely varied.

To summarize the present invention, it provides novel water clear, non-aqueous mineral, vegetable and animal oils dissolved in low molecular weight alcohols and solubilized by light molecular weight fatty alcohols, will be highly effective in silicone protective lotions to give effective cutaneous protection against soaps, detergents, alkalies, sensitizers, solvents, plasticizers and allergens as well as in various aerosol preparations which are used in the cosmetic field, as, for example, for hair and nail lacquers and which will be useful for the dispersion of cutting oils, drying oils, solvent oils, insect repellants, insecticides, and pigments in the paint industry.

It is the primary object of the present invention to provide a novel solubilized mineral, vegetable and animal oil composition in which such oils will be dispersed in low molecule weight alcohols and which may be the product used as a base for cosmetic preparations such as hair tonics, hand lotions, sunscreening preparations, and after-shave lotions, as well as facial astringents, anti-perspirant preparations, and anti-dandruff preparations.

In the hair lotion preparations, there may be added lanolin derivatives, antiseptic rubefacients, estrogenic hormones, methyl sulfoxide, dithiocarbamates, methoxychloracetic acid, solubilized amino acids.

In the silicone protective preparations, there may be added soluble silicones, lanolin derivatives, and anti-septics.

In the after-shaving lotions, there may be added anti-septics, astringents, as aluminum, zinc or zirconium salts, and also antibiotics as tyrothricin, neomycin, and bacitracin.

In the acne preparations, there may be added sulfur, polysulfides, resorcin, vitamins A and D, antibiotics as tyrothricin, neomycin, and bacitracin.

In the fungicidal preparations, there may be added salicylic acid, benzoic acid, acids, as propionic thio-glycollic and undecylinic acids, and their salts.

In the anti-dandruff lotions, there may be added sulfur, resorcinol, salicylates, organic sulfides, dithiocarbamates, oxy-acetamides, and oxy-acetic acids.

In the hair lacquer preparations, there may be added silicones, casein, protein hydrolysates and lanolin derivatives.

In the permanent waving solutions, there may be added the thioglycolic derivatives, polyvinylpyrrolidine and casein or protein hydrolysates.

These added components will not effect the solubilizing effect of the above high molecular weight fatty alcohols.

Normally mixtures of low molecular weight alcohols and high molecular weight oils of mineral, vegetable or animal origin with 5 to 15% of the above fatty alcohols will not separate, and will have high pharmaceutical and therapeutic effectiveness, cosmetic consumer acceptance, industrial applicability and efficiency.

Surprisingly high molecular weight fatty alcohols containing 12 to 18 carbon atoms result in solubilizing of mineral oils and vegetable oils on the one hand in ethyl

and isopropyl alcohol and on the other hand in a manner, which remarkably is not achieved when the corresponding fatty acid is used by itself in the same amounts or in combination with the fatty alcohol.

To illustrate this point, the following combinations were made up in parts by weight:

Ingredients	Examples				
	XXIII	XXIV	XXV	XXVI	XXVII
Mineral oil	40	40	40	40	40
Ethyl alcohol	40	40	40	40	40
Lauryl alcohol			15	10	10
Myristyl alcohol			5		
Lauric acid		10		10	10
Myristic acid		10			
(all parts being by weight)					

In connection with the above composition, composition XXIII immediately tends to produce a cloudiness and precipitation and separation of the oil and alcohol.

Composition XXIV initially tends to be clear but upon standing or shelving develops cloudiness which slowly increases with time and gives a precipitation.

Compositions XXVI and XXVII also tend to cloud with time and give a precipitation, although the development of cloudiness and the precipitation is much slower than in case of composition XXIV.

However, with composition XXIII, the separation and cloudiness takes place immediately, whereas with composition XXIV there is considerable development of cloudiness and precipitation within 12 to 24 weeks while in compositions XXVI and XXVII a similar development of cloudiness and precipitation, as is true of composition XXIV, would take about three to four weeks longer.

On the other hand, composition XXV remains bright and clear with a shelf life of twelve months and longer, without any appearance of cloudiness or precipitation and it would appear from the experiments being carried on that either under winter or summer conditions the composition XXV remains clear and soluble indefinitely.

It has been found that sudden changes in temperature tend to catalyze the development of cloudiness, separation and precipitation in compositions XXIV, XXVI and XXVII whereas with composition XXV such catalyzing effect is altogether absent.

Upon substituting oleic and ricinoleic acid for lauric and myristic acid, the same result was observed in respect to cloudiness and precipitation after several weeks of standing, particularly under sudden changes of temperature.

It appears that the cloudiness and precipitation is due to the carboxyl group, which tends to activate any small quantities of water which might be present or become adsorbed upon storage.

Initially the corresponding high molecular weight fatty acids appear to give miscibility but such miscibility is not permanent.

While there has been herein described a preferred form of the invention, it should be understood that the same may be altered in details and in relative arrangement of parts within the scope of the appended claims.

The present application is a continuation-in-part of ap-

plications Serial Number 349,311, filed April 16, 1953, now abandoned and Serial Number 465,443, filed October 28, 1954, now abandoned.

Having now particularly described and ascertained the nature of the invention, and in what manner the same is to be performed, what is claimed is:

1. A clear, non-aqueous solubilized liquid composition consisting of a low molecular weight aliphatic alcohol having 1 to 3 carbon atoms and an oil containing 24 to 100 carbon atoms, normally immiscible in said low molecular weight aliphatic alcohol, and said oil and alcohol being made miscible and solubilized in each other by a high molecular weight fatty alcohol having 12 to 24 carbon atoms, said solubilized composition consisting essentially of 20-50% of the oil, 20-50% of the low molecular weight aliphatic alcohol and 5-20% of the high molecular weight fatty alcohol, said percentages being by weight.

2. The composition of claim 1, in which the low molecular weight aliphatic alcohol is selected from the group consisting of methyl alcohol, ethyl alcohol and isopropyl alcohol and in which the high molecular weight aliphatic alcohol has from 12 to 24 carbon atoms and constitutes 5% to 20% of the solubilized composition.

3. The composition of claim 1, in which the high molecular weight fatty alcohol consists of a mixture of lauryl alcohol and myristyl alcohol and constitutes between 10% to 20% of the solubilized composition with the balance consisting of equal parts of an oil selected from the group consisting of animal, vegetable and mineral oils and an alcohol selected from the group consisting of methyl, ethyl and isopropyl alcohol, the proportion of lauryl alcohol being 2 to 4 times the proportion of myristyl alcohol.

4. A clear non-aqueous solubilized liquid composition consisting of a low molecular weight aliphatic alcohol containing 1 to 3 carbon atoms and an oil containing 24 to 100 carbon atoms, normally immiscible in said low molecular weight aliphatic alcohol, and said oil and alcohol being made miscible and solubilized in each other by inclusion of a minor proportion of a high molecular weight aliphatic alcohol having 12 to 24 carbon atoms, said solubilized composition consisting essentially of 20 to 50% of mineral oil, 20 to 50% of ethyl alcohol and 5-20% of the high molecular weight fatty alcohol, said percentages being by weight.

5. A clear, non-aqueous solubilized liquid composition consisting of ethyl alcohol and petrolatum oil in equal parts constituting about 80-90% of the composition which have been solubilized in each other by 5 to 20% of a high molecular weight aliphatic alcohol having 12 to 24 carbon atoms.

6. The composition of claim 5 in which the high molecular weight aliphatic alcohol is included in an amount ranging between 10% and 20%.
